UNITED STATES PATENT OFFICE.

JOHN E. WALTER, OF COLLINWOOD, OHIO.

DISH-WASHER.

No. 927,905.

Specification of Letters Patent. Patented July 13, 1909.

Application filed August 7, 1908. Serial No. 447,429.

To all whom it may concern:

Be it known that I, JOHN E. WALTER, a citizen of the United States, residing at Collinwood, in the county of Cuyahoga and State of Ohio, have invented certain new and useful Improvements in Dish-Washers, of which the following is a specification.

This invention relates to dish washing machines and refers especially to one which automatically cleanses the dishes placed in the same.

An object of this invention is to cleanse the dishes and at the same time to sterilize the same.

15 The invention has another object the provision of a device wherein the dishes may be held and dried after the washing.

The invention further designs a device of this character which is constructed on sanitary principles insomuch that no brushes or the like are employed which are liable to collect foreign substances from the water and dishes with which they are engaged, the water which is used to cleanse the dishes is 25 immediately carried off through a drain and is not utilized a second time as is the case in the majority of devices of this nature.

A still further object of this invention is the provision of a dish washer which may be 30 adjusted to conform to the sizes of the different types of dishes placed therein.

Other objects and advantages will be apparent from the following description and it will be understood that changes in the specific structure shown and described may be made within the scope of the claims without departing from the spirit of the invention.

In the drawings forming a portion of this specification, and in which like numerals of 40 reference indicate similar parts in the several views, Figure 1 is a front elevation of the device, Fig. 2 is a top plan of the same, Fig. 3 is a longitudinal vertical section of the device, Fig. 4 is a transverse section of the 45 same.

Referring now to the drawings, 10 denotes a frame which is of rectangular formation and is provided with a drip pan 11 which is of funnel shape and is provided with a drain 50 pipe 12 at its central portion which extends downwardly and carries off the water from the pan 11. The frame 10 is provided with two sides 13 and 14 which extend upwardly and support a suitable cover 15 disposed 55 across the same. The pan 11 is provided with two parallel longitudinally disposed

rods 16 upon which are adapted to rest the dishes and the like in the device. A water feed pipe 17 is positioned centrally in the drain pipe 12, the water feed pipe 17 being 60 considerably smaller than the pipe 12, and extending upwardly through the drip pan 11 to a position directly beneath the rods 16 where a rose sprinkler 18 is employed for the even distribution of the water. The supply 65 pipe 17 is provided with a lateral extension 19 which extends beyond the side 14 where it is curved upwardly and passed over the cover 15 to the central portion thereof where it is extended through the cover 15 and supports 70 a rose spray nozzle 20 thereon.

The plate 23 is provided near its upper edge with inwardly extending sleeves 22 through which is slidably engaged a rod 28 secured at one extremity to the plate 24 and 75 connected to a hand lever 27 at its outer extremity. The plate 24 is provided with two of these rods 28 which extend through the sleeves 22 and engage a cross arm disposed upon the lever 27. The plate 23 is provided 80 near its lower edge with inwardly extending sleeves 21 which are provided with outwardly extended arms 29 for engagement with the lower extremity of the lever 27, the lever 27 being intermediately pivoted upon 85 an extension to the side 13, for the purpose of reciprocating the side 13 upon the actuation of the lever 27. The opposite plate 24 is provided with centrally extended rods 30 which engage in the sleeves 21 for the purpose 90 of maintaining the plates 23 and 24 in a vertical position when the same are actuated. The plates 23 and 24 are provided upon their inner opposite faces with cleats 25 and 26 which are positioned toward the lower edges 95 thereof for the purpose of receiving the edges of the dishes to be cleansed. The connections of the outer extremities of the rods 28 and arms 29 to the hand lever 27 are of necessity loose to allow for the rotation of the 100 lever 27 as the same is actuated.

The operation of the device is as follows: The lever 27 is actuated to draw upon the rod 28 which slides the supporting plate 24 centrally of the device pushing the rod 29 and 105 causing the supporting plate 23 to be moved centrally likewise. The device is thus adjusted to the size of the plate to be washed which is now inserted between the supporting plates 23 and 24 engaging the edges 110 thereof upon the cleats 25 and 26. The water is now turned on and is fed upwardly

through the pipe 17 and branch 19 where it is sprayed from the rose sprinkler 18 and spray nozzle 20 against the opposite sides of the plate positioned in the device. The plate after being washed is withdrawn from the rear end of the device and gives place to a second plate which is inserted between the flaring ends of the sides 13 and 14 and the supporting plates 23 and 24. If it is desired 10 the plate may be left in position until the same is dried thus employing the device as a drying rack.

What is claimed is:—

1. A device of the class described comprising a body portion, adjustable supporting plates mounted in said body portion and means for spraying the water upon the opposite sides of a plate positioned upon said supporting plates.
2. A device of the class described comprising a body portion, supporting plates slidably disposed in said body portion, a lever carried by said body portion for actuating said plates, a feed pipe positioned in the bottom

of said device, a branch pipe carried by said feed pipe and extended to the upper portion of said device, nozzles disposed upon the extremities of said pipes, a drip pan disposed at the lower end of said body portion and a drain pipe disposed about said feed pipe and connected to said drip pan.

3. A dish washer having means for adjustably engaging dishes placed therein and means for feeding water against the opposite sides of the dish supported in said device.

4. In a device of the character described the combination with a body portion, of adjustable supporting plates mounted in said body portion, a lever pivotally supported upon the side of said body portion and of means for connecting said lever to said supporting plates for reciprocating the same.

In testimony whereof I affix my signature, in presence of two witnesses.

JOHN E. WALTER.
